WEFT REPLENISHING MECHANISM FOR
LOOMSAlbert Cederlund, Worcester, Mass., assignor to
Crompton & Knowles Loom Works, Worcester,
Mass., a corporation of Massachusetts

Application March 17, 1937, Serial No. 131,430

6 Claims. (Cl. 139—232)

This invention relates to weft replenishing mechanisms for looms and it is the general object of the invention to provide improvements in means for setting the transfer mechanism.

5 In mechanisms of the type to which my invention more particularly relates there is employed a magazine holding reserve bobbins and a transfer mechanism including a transerrer arm carrying a latch which is moved by a bunter 10 on the lay when a transfer is to occur. The latch is ordinarily held in transferring position by mechanism which is reset at the end of the transferring stroke of the lay, that is, at front center as set forth hereinafter. It is an important 15 object of my present invention to provide mechanism for setting the latch and thereafter breaking the connection so that the latch controller can be reset independently of the setting mechanism. As shown in the drawings the breaking of 20 the connections is effected by a movement of one of the parts of the connection as said part reaches the end of its setting motion.

It occasionally happens that a shuttle to be replenished is not completely boxed, in which case 25 the transfer is revoked by a shuttle feeler while the lay is still a considerable distance from front center. It is another object of my present invention to provide connections for setting the latch and shuttle feeler so constructed that the 30 connections will be interrupted after the latch and shuttle feeler are fully set for transfer and before the time for revocation arrives in the forward beat of the lay. This result may conveniently be accomplished by causing cooperation 35 between a part included in the connections and some other part of the loom operative to break the connections as said part of the latter reaches the end of its setting stroke.

In the form of loom to which my invention 40 more particularly relates there is employed a rocking magazine which shifts its position depending upon which weaving shuttle is active. It is desirable that the magazine retain a selected position throughout a transferring operation and 45 this is accomplished by a positioning lever or similar part which remains in its magazine setting position for an appreciable time after the lay leaves front center to prevent breakage between the transerrer arm and the magazine. I 50 make use of a connection from the magazine positioning lever to set the transfer latch by means of an actuator or the like which is connected to the lever. The actuator is therefore required to remain in transfer position for a period starting 55 some time before and continuing to a point after

the front center position of the lay. It is a further object of my present invention to cause the actuator to move out of force transmitting relation with respect to the latch and shuttle feeler after setting the latter so that said actuator and 5 its lever may be maintained in transfer position to hold the magazine correctly while at the same time permitting either a revocation of the transfer or resetting of the transerrer latch.

With these and other objects in view which will 10 be apparent as the description proceeds, my invention resides in the combination and arrangement of parts hereinafter described and set forth.

In the accompanying drawings, wherein a convenient embodiment of my invention is set forth, 15

Fig. 1 is an end elevation of a loom having my invention applied thereto, certain parts being in section.

Fig. 2 is an enlarged end view of the magazine taken from the center of the loom, the lay being 20 shown in section and the magazine set for transfer.

Figs. 3, 4, 5 and 6 are diagrammatic views showing certain parts of the invention in different positions.

Referring to Fig. 1, the loom frame 10 has a top crank shaft 11 and a bottom shaft 12 turning at half the speed of the top shaft. Connectors 13 drive the lay L from the top shaft, the lay turning about the usual rocker shaft 14 and 30 having a shuttle box B to receive a shuttle S. A bunter 15 on the lay is adapted for engagement with a transerrer latch 16 normally down as shown in Fig. 1. The latch is pivoted as at 17 to a transerrer arm 18 movable about a stud 19 and having a hammer 20 to engage a reserve bobbin in transfer position. Except for slight modification the matter thus far described may be of the usual construction found in weft replenishing looms.

An electrical weft detector D controls a solenoid 25 mounted on a normally stationary lever 26 pivoted to a fixed stud 27. A selector mechanism designated generally at 28 is mounted on lever 26 and is positioned by a rod 29 connected 45 to a rocking lever 30. The latter moves about a stud 31 mounted on a fixed stand 32 and has the lower end thereof attached to connections 33 extending to a shuttle box or pattern mechanism not shown.

A cam 35 is secured to the bottom shaft and is connected to a regularly acting lever 36 the forward or left hand end of which as viewed in Fig. 1 has a rising motion every second beat of the loom. A lifting dog 37 is mounted on lever 50

36 and acts to lift lever 26 when a transfer is to occur.

The detector D excites the solenoid 25 through a battery P and wires 40, 41 and 42. When the detector indicates weft exhaustion current will flow through the circuit shown in Fig. 1 to energize the solenoid, the effect of which is to set the selector mechanism so that a transfer will occur upon a subsequent arrival of the shuttle 10 in the box B.

The forward end of lever 26 is connected to an upright rod 45 the connections of which will be described hereinafter, while the rear end of said lever 26 is adapted for engagement with a hook 46 extending upwardly to a lever 47 from which extends forwardly a link 48 connected as at 49 to a rocking magazine M. The latter rocks about a fixed axis 50 carried by a bracket 51 extending from the loom arch 52 to the breast beam 53. The magazine is provided with front and back reserve bobbin guideways 55 and 56, respectively, which direct bobbins downwardly to front and back giveaway or support mechanism 57 and 58, respectively. The magazine can be rocked so that one or the other of the low bobbins in the two stacks will be under the transfer hammer 28 when the magazine is set for transfer.

The mechanism shown in the lower part of Fig. 1 together with the magazine may be substantially the same as that shown in co-pending application filed by Turner Serial No. 129,245. Briefly, the magazine will be at rest with the lowest bobbin of the rear stack under the transfer hammer awaiting transfer and this condition of rest will continue during shifting of the shuttle boxes not shown but located on opposite sides of the loom and cooperating with a plurality of weaving shuttles any one of which may become active for any given number of picks. If the detector indicates exhaustion in a weaving shuttle corresponding to the rear stack the rod 29 will at that time be in rear position by action of connections 33 and the ensuing rocking of lever 26 in a right hand direction around stud 27 will leave the magazine in its normal position of rest because of the fact that hook 46 has been moved beyond the range of action of the rear end of lever 36. Should a transfer be called from the front stack of the magazine, however, the hook 46 will remain in the position shown in Fig. 1 and the subsequent rocking of lever 26 will depress hook 46 and the latter will act through the mechanism indicated in Fig. 1 to rock the magazine in a left hand direction around stud 50.

The construction of the magazine is such that it is desirable to have it maintained in its angular position either to the right or to the left throughout the transferring period. As is usual in weft replenishing mechanisms the transerrer latch will be engaged by the lay bunter some time before the lay reaches front center and will remain in contact with the bunter during backward motion of the lay until the transerrer arm 65 has been raised to its normal elevated position. During the transferring interval, therefore, lever 26 will be held with the forward end thereof up, the interval extending into the first part of the backward motion of the lay following transfer. Dwell 59 of the cam 35 acts to maintain the magazine at rest and rod 45 up throughout the transferring interval. A bobbin placing guide 105 assists in holding a bobbin in transfer position and would interfere with the transerrer arm 75 during the transferring interval if the magazine

should rock at that time. The dwell 59 is long enough to hold the magazine against rocking motion during the transferring interval.

My invention relates more particularly to the mechanism for setting the transfer latch and shuttle feeler to be described, and also for permitting revocation of the transfer and resetting of the latch and shuttle feeler. In carrying my invention into effect, I provide the upper end of rod 45 with a head or actuator 60 the top of which is formed with a hook 61 and a lifting shoulder 62. The hook is spaced from the shoulder to define an opening 63, while the lower end of the actuator is formed with a cam surface 65 and a dwell surface 66 which in the raised position of the actuator is substantially concentric with stud 19. The transerrer arm has extending laterally therefrom a pin 67 for engagement with the cam and dwell surfaces. A small return lever 68 is pivoted as at 69 to the transerrer arm and is urged forwardly by a light tension spring 70 interposed between the transfer arm and said lever 68. The latter has a stud 71 for engagement with the rear substantially straight surface 72 of the actuator.

The shoulder 62 is normally positioned to have lifting engagement with a pin 75 carried by a lever 76 secured to a stub shaft 77 rockable in bracket 51. The forward end of lever 76 has a pin 78 received by a slot 79 in a rod head 80 on the upper end of rod 81 pivoted as at 82 to the latch holder 83. The lever 76 is fixed to stub shaft 77 by a set screw 84, and the inner end of the shaft 77 carries a bell crank lever 85 secured thereto by set screw 73, see Fig. 2, having a depending arm 74 connected to a rearwardly extending rod 86 connected as at 87 to a shuttle feeler 88 pivoting about a fixed stud 89. Lever 85 has a rearwardly extending arm 90 having pivoted thereto as at 91 a spring rod 92 cooperating with a compression spring 93 and tending to hold the arm 90 either against an upper stop screw 94 or a lower similar stop screw 95. These stop screws limit the lever 85 and correspondingly the lever 76, the spring 93 serving as a yielding lock to hold these levers in either of their extreme positions.

In operation, after an indication of weft exhaustion has been given as already described, lever 26 will rock in a right hand direction as viewed in Fig. 1, and rod 45 together with its actuator 60 will be raised, the actuator starting from the full line position shown in Fig. 3 and moving upwardly until the shoulder 62 engages the pin 75, after which continued rising of the actuator will rock lever 76 in a left hand direction as viewed in Fig. 3 and cause a corresponding rocking of lever 85. During the upward motion of the actuator the time will come when the spring 93 will assume control of lever 85 and rock the same in a right hand direction as viewed in Fig. 2 to move the shuttle feeler 88 rearwardly to the position shown in that figure.

Continued upward motion of the actuator 60 will bring the cam surface 65 into engagement with pin 67 on the transerrer arm, the latter being in its normal raised position at the time and as said surface engages the pin the actuator will be moved rearwardly or to the right from the position of Fig. 4 to that of Fig. 5, the pin 67 being at the lower forward end of surface 65. The opening 63 between the hook and the lifting shoulder of the head is so placed as to permit this rearward movement of the head, the pin 75

passing through the opening as the parts move to the position shown in Fig. 5.

During the rocking of shaft 77 the rod 81 is depressed so that the latch 16 is raised from its normally down position as shown in full lines in Fig. 3 to the raised dotted position in Fig. 4, in which latter position the latch is maintained in the path of bunter 15 by action of the spring 93, as will be apparent from an inspection of Fig. 2. It is to be remembered that under these conditions the shuttle feeler is in the rear detecting position shown in Fig. 2.

The latch is now set for a transferring operation and one of two conditions can follow, either a normal transfer can take place, or the empty shuttle will fail to be properly boxed and will act on the shuttle feeler to revoke transfer. Should a normal transfer ensue the lay bunter will engage and move the latch forwardly to lower the transerrer arm in the usual manner, the parts moving to the position shown in Fig. 6 and the insertion of the incoming bobbin being completed when the lay reaches front center. During the latter part of the forward motion of the lay, the lower end of the shuttle feeler will engage the box back 100 and be rocked forwardly, or to the right as viewed in Fig. 2, to move lever 85 in a counter-clockwise direction, thereby rocking shaft 77 and causing the lever 85 ultimately to be positioned by stop screw 95. During this rocking of shaft 77 the lever 76 will be moved in a right hand direction back to its normal position or to the position of Fig. 6. This leaves pin 75 a considerable distance below the lifting shoulder 62, and slot 79 accommodates the motion of stud 78, the latch being still raised. As already described rod 45 will be maintained in raised position during transfer and will therefore be in the high position shown in Fig. 6 when lever 76 returns to its normal position.

During the following rearward movement of the lay immediately subsequent to transfer, the latch will follow the lay during the remainder of the transferring interval and after the bunter has moved away from the latch, freeing the latter so it can fall to normal position, the cam can act to lower the forward end of lever 26, the transerrer arm being now up, as is usual in such motions, where it cannot interfere with the magazine should the latter rock. The resultant downward motion of actuator 60 will move the cam surface 65 along the underside of pin 67, permitting the actuator to have a downward and forward motion to cause pin 75 to enter the space 63, thereby returning the actuator to a position where it can engage pin 75 when rising again. Spring 70 assists in this placing of the actuator through action of the lever 68.

Should the shuttle fail to be boxed, after a transfer is called, the front wall 101 of the shuttle S will engage the shuttle feeler when the parts are in the full line position in Fig. 5 and will move the feeler forwardly a little earlier than normal, rocking lever 76 to the dotted position of Fig. 5. Under these conditions transfer is prevented and the transerrer arm therefore remains raised with the pin 67 holding the actuator 60 rearwardly to permit free motion of the pin 75 without interference on the part of the lifting shoulder 62. The parts will remain in this position until the time arrives for the actuator to descend, whereupon the normal conditions will be reestablished as already described.

The magazine set forth hereinbefore is not a part of my invention but is set forth and claimed

in the aforesaid application of Turner, my invention being directed to the parts associated with the interruption of the operative connections between the lever 26 and the transfer latch 16.

From the foregoing it will be seen that I have provided means for setting the transfer latch so constructed that the chain of connections between the lever 26 and the latch can be interrupted at the head 60, the latter moving temporarily out of controlling relation with respect to pin 75. As a result of this interrupted connection it is possible to revoke a transfer or reset the magazine by rocking of lever 85 while the head is still in raised position, a condition made necessary by the fact that the magazine rocks. It will further be seen that raising of the head 60 effects the interruption of the connections, this interruption being effected upon the completion of the upward motion of the head independently of movement of the transerrer arm. This latter condition is made possible by the dwell 66.

Having thus described by invention it will be seen that changes and modifications may be made therein by those skilled in the art without departing from the spirit and scope of the invention and I do not wish to be limited to the details herein disclosed, but what I claim is:

1. In a weft replenishing loom having a lay provided with a bunter, a magazine movable to present any one of a plurality of reserve bobbins in position for transfer, a transerrer arm which in normal position is out of interfering relation with respect to the magazine but which moves into interfering relation with respect to the magazine when transferring the reserve bobbin in transfer position, a member movable at the time of transfer to move the magazine to place a reserve bobbin for transfer, a latch movable from normal position to transfer position in the path of the bunter, a shuttle feeler to assist in resetting the latch, a train of mechanism connecting the member to the shuttle feeler and latch to move the latter to transfer position and move said shuttle feeler to shuttle feeling position when said member moves the magazine, said train of mechanism including two cooperating parts normally positioned to transmit a force from the member to said latch and feeler, and means to move said parts relatively to each other out of force transmitting relationship after the latch and feeler have been set for transfer to render said shuttle feeler capable of movement independently of said train of mechanism during the time that the member is holding the magazine in position for transfer.

2. In a weft replenishing loom having a lay provided with a bunter, a magazine movable to present any one of a plurality of reserve bobbins in position for transfer and having a part movable in a given path, a transfer arm which in normal position is out of interfering relation with respect to the magazine but which moves along a path intersecting the path of the magazine when transferring the reserve bobbin in transfer position, a transfer latch connected to the transerrer arm and movable from normal position to transfer position in the path of the bunter to be engaged with the latter during portions of front and back motions of the lay, a shuttle feeler connected to the latch and capable of assisting in resetting said latch, a member connected to the magazine and movable when a transfer is called to move the magazine to place a reserve bobbin for transfer and hold said magazine in transfer position during the aforesaid portions of forward and

backward motions of the lay, a train of mechanism connecting the member to the latch and feeler to move said latch to transfer position and move the shuttle feeler to a position for engagement with the lay as the latter moves forwardly, 5 said train including two members normally positioned for mutual engagement, and means operating before the lay reaches the end of its forward stroke to move said parts out of engaging relationship and render the shuttle feeler capable of 10 movement by forward motion of the lay to assist in resetting the latch during the time that the member maintains the magazine placed for transfer and during the time that the transerrer arm moves across the given path of the magazine part. 15

3. In a weft replenishing loom having a lay provided with a bunter, a magazine movable to present any one of a plurality of reserve bobbins in position for transfer and having a part movable in a given path, a transerrer arm which in normal 20 position is out of interfering relation with respect to the magazine but which moves along a path intersecting the path of the magazine when transferring the reserve bobbin in transfer position, 25 a member movable when a transfer is called to move the magazine to place a reserve bobbin for transfer and hold the magazine in such position during parts of consecutive forward and rearward motions of the lay, a transerrer latch connected to said transerrer arm and movable from 30 normal position to transfer position in the path of the bunter, a shuttle feeler connected to and controlling the latch and movable when a transfer is called into position to be engaged and moved 35 by the lay when the latter moves forwardly to assist in resetting the latch to normal position, a train of mechanism connecting the member to the latch and shuttle feeler effective when said member moves to position the magazine for the transfer to move the latch to transfer position and 40 move the shuttle feeler into position for engagement with the lay when the latter moves forwardly, said train including two parts normally in force transmitting position with respect to each 45 other, and means acting subsequently to movement of the latch to transfer position and movement of the shuttle feeler to lay engaging position to move said parts out of force transmitting relationship to render the shuttle feeler capable of movement by the lay when the latter moves forwardly to assist in a resetting of the latch during the time that the member maintains the 50 magazine in transferring position.

4. In a weft replenishing loom having a lay provided with a bunter, a magazine movable to present any one of a plurality of reserve bobbins in position for transfer and having a part movable in a given path, a transerrer arm which in normal 55 position is out of interfering relation with respect to the magazine but which moves along a path intersecting the path of the magazine when transferring the reserve bobbin in transfer position, a member movable when a transfer is called to move the magazine to place a reserve bobbin for transfer and hold the magazine in such position during parts of consecutive forward and rearward motions of the lay, a transerrer latch connected to said transerrer arm, a positioning element 60 connected to the latch to move the latter from normal position to transfer position in the path of the bunter, a shuttle feeler connected to 65

and moving with the positioning element and movable when a transfer is called into position to be engaged by the lay when the latter moves forwardly, an actuator connected to the member and effective when said member moves to position the magazine for the transfer to move the positioning element and thereby cause the latch to move to transfer position and the shuttle feeler to move into position for engagement with the lay when the latter moves forwardly, and means acting subsequently to movement of the latch to transfer position and movement of the shuttle feeler to lay engaging position to move said actuator relatively to the positioning element and out of force transmitting relation with respect to the latter to render said shuttle feeler capable by forward motion when in engagement with the lay of assisting in a resetting of the positioning element independently of said member and during the time that said member is holding the magazine in transfer position. 10 15 20

5. In a weft replenishing loom having a lay with a bunter, a latch normally out of the path of the bunter but movable to transfer position into the path of the bunter to be operated by forward motion of the lay, a normally raised transerrer arm connected to and operated by motion of the latch, an actuator having a movement when a transfer is called, said actuator having a cam face, means on the transerrer arm 30 to engage the cam and shift the actuator when the latter moves, a shuttle feeler to be moved toward the lay and movable by the latter before completion of a transferring operation, and setting mechanism connected to the latch and shuttle feeler and movable by the actuator preparatory to transfer to move the latch into the path of the bunter and move the shuttle feeler toward the lay, the transerrer arm being lowered as the lay advances by engagement of the latch 35 and bunter and said means shifting the actuator out of control of the setting mechanism, whereby the shuttle feeler is movable by the lay while the bunter and latch are still in engagement. 40

6. In a weft replenishing loom having a lay provided with a bunter, a latch normally out of the path of the bunter but movable to transfer position in said path, a transerrer arm connected to and operated by said latch when the latter is moved by the bunter, an actuator having an operating movement when transfer is called, a shuttle feeler normally out of engagement with the lay but movable into a position for engagement with the lay preparatory to transfer, setting mechanism having an interruptable connection with the actuator, said setting mechanism connected to the latch and shuttle feeler and movable by the actuator by a force transmitted through the interruptable connection to move the latch into the path of the bunter and move the shuttle feeler into position for engagement with the lay, forward motion of the lay causing engagement of the bunter and the latch to operate the transerrer arm, and means moving with the transerrer arm when the latter operates to interrupt the connection between the setting mechanism and actuator while the latch and bunter are engaged, the shuttle feeler being thereby capable of movement by the lay independently of the actuator. 45 50 55 60 65 70
